(57) **CLAIM**

The ornamental design for a sorbent consumable base, as shown and described.

DESCRIPTION

FIG. 1 is a top, front, right perspective view of a sorbent consumable base according to the present design;

FIG. 2 is a top, front, left perspective view of the sorbent consumable base of FIG. 1;

FIG. 3 is a top, rear, left perspective view of the sorbent consumable base of FIG. 1;

FIG. 4 is a top, rear, right perspective view of the sorbent consumable base of FIG. 1;

FIG. 5 is a front elevational view of the sorbent consumable base of FIG. 1;

FIG. 6 is a rear elevational view of the sorbent consumable base of FIG. 1;

FIG. 7 is a left elevational view of the sorbent consumable base of FIG. 1;

FIG. 8 is a right elevational view of the sorbent consumable base of FIG. 1;

FIG. 9 is a top plan view of the sorbent consumable base of FIG. 1; and,

FIG. 10 is a bottom plan view of the sorbent consumable base of FIG. 1.

The broken lines illustrate portions of the article and form no part of the claimed design.

1 Claim, 8 Drawing Sheets
